CLAIM

The ornamental design for an ash receptacle, as shown and described.

DESCRIPTION

FIG. 1 is a perspective view of an ash receptacle showing my new design;

FIG. 2 is a right side elevational view thereof, the left side being substantially a mirror image thereof;

FIG. 3 is a top plan view thereof; and

FIG. 4 is a rear elevational view thereof.

FIG. 1

FIG. 3

FIG. 2

FIG. 4
